UNITED STATES PATENT OFFICE

169,984

SPRAY-TYPE DISPENSER FOR LIQUIDS

Kenneth K. Miller, Kalamazoo, Mich., assignor to Miller Protecto Products Company, Kalamazoo,
Mich., a corporation of Michigan

Application July 31, 1952, Serial No. 20,861

Term of patent 14 years

(Cl. D62—2)

To all whom it may concern:

Be it known that I, Kenneth K. Miller, a citizen of the United States of America, residing at 1930 Dickey Road, Kalamazoo, in the county of Kalamazoo and State of Michigan, have invented a new, original, and ornamental Design for a Spray-Type Dispenser for Liquids, of which the following is a specification, reference being had to the accompanying drawings, forming a part thereof.

In the drawings:

I claim:

The ornamental design for a spray-type dispenser for liquids, substantially as shown.

KENNETH K. MILLER.
